CLAIM

The ornamental design for a remembrance plaque, substantially as shown and described.

DESCRIPTION

FIG. 1 is a rear elevational view of an ornamental remembrance plaque, showing our new design,

FIG. 2 is a side elevational view thereof,

FIG. 3 is a perspective view of the plaque, looking from the rear side thereof, and

FIG. 4 is a perspective view of the plaque, looking from the front side thereof.

The dotted line showing of wording in FIG. 4 is for illustrative purposes only.

FIG. 3.

FIG. 4.
